US0D1023627S

(12) United States Design Patent (10) Patent No.: US D1,023,627 S
(45) Date of Patent:  Apr. 23, 2024

(54) WORKSTATION

(71) Applicant: AMQ Solutions, LLC, Santa Clara, CA (US)

(72) Inventors: Kin Fui Chong, Jurong West (SG); Tsung-Hsien Ho, Taichung (TW); Soo Beng Khoo, Telok Blangah (SG); Dennis Ding Yik Ming, Puchong (MY); Jiwon Shin, Seoul (KR)

(73) Assignee: AMQ Solutions, LLC, Santa Clara, CA (US)

() Term: 15 Years

(21) Appl. No.: 29/803,759

(22) Filed: Aug. 16, 2021

(51) LOC (14) Cl. 06-03

(52) U.S. Cl.

USPC D6/643

(58) Field of Classification Search

USPC D6/332, 641, 642, 643, 653, 653.1, D6/654.21, 714

CPC A47B 21/00; A47B 21/02; A47B 3/083; A47B 41/00; A47B 19/06

See application file for complete search history.

(57) CLAIM

The ornamental design for a workstation, as shown and described.

DESCRIPTION

FIG. 1 is a top front/right perspective view of an embodiment of a workstation;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom/right perspective view thereof.

1 Claim, 7 Drawing Sheets
